UNITED STATES PATENT OFFICE.

EDMUND ZEH, OF BUFFALO, NEW YORK, ASSIGNOR TO NIAGARA MACHINE & TOOL WORKS, OF BUFFALO, N. Y.

DOUBLE-SEAMING MACHINE.

SPECIFICATION forming part of Letters Patent No. 787,549, dated April 18, 1905.

Application filed October 9, 1902. Serial No. 126,461.

To all whom it may concern:

Be it known that I, EDMUND ZEH, a subject of the German Emperor, residing at Buffalo, in the county of Erie and State of New York, have invented a new and useful Improvement in Double-Seaming Machines, of which the following is a specification.

This invention relates to a machine for securing the heads or ends on metallic cans, boxes, or cases of that kind in which the can-body is provided with an outwardly-projecting marginal flange at its end and the head is provided with a marginal flange which projects outwardly beside the body-flange when the head-blank is placed on the body, said flanges being bent over so that they interlock to form a double seam or lock-joint. The machine is of that type which is provided with a chuck in which the can-body and head are firmly held together in the proper relation and dies which are moved toward the can and have faces suitably shaped to roll or turn over the flanges of the can-body and head-blank to form the double seam. The double seam when thus formed is more or less open, and while it securely holds the parts from separation it does not make a sufficiently tight joint for many purposes unless the seam is afterward soldered or pressed or squeezed to tightly close the joint or force the interlocking parts into intimate contact.

The object of the invention is to provide an efficient machine which is of simple and inexpensive construction and in which the double seam is first formed and then squeezed, pressed, or tightly closed to finish the same at successive operations by a single set of dies.

In the accompanying drawings, consisting of four sheets, Figure 1 is a side elevation, partly in section, of a can-heading machine embodying the invention. Fig. 2 is a plan view thereof, the upper head of the chuck being partly broken away. Fig. 3 is a broken sectional elevation in line 3 3, Fig. 1, showing the clutch mechanism. Fig. 4 is a broken vertical sectional elevation through the lower portion of the machine in line 4 4, Fig. 2. Fig. 5 is a broken horizontal section, partly in plan, through the lower portion of the ma-

chine in line 5 5, Fig. 4. Fig. 6 is a fragmentary sectional elevation through the lower chuck-head and one of the seaming-dies, showing the parts in the position they occupy when the seam has been formed, but before it has been pressed. Fig. 7 is a similar view, showing the parts in position to press the seam. Fig. 8 is an enlarged, fragmentary section of the lower chuck-head and a seaming-die, showing the parts in their initial position. Fig. 9 is a similar view showing the position of the parts after the seam has been pressed. Fig. 10 is an enlarged detail section of the clutch-bolt, latch, and associated parts.

Like letters of reference refer to like parts in the several figures.

The machine shown in the drawings and hereinafter described is designed for operation upon square cans, boxes, or cases; but it will be understood that by suitably changing the coöperating faces of the can-holding mandrel or chuck-head and seaming-dies the machine can be readily adapted for operation upon circular cans or cans of other shapes. The combined double seam forming and pressing die is also capable of use in joining two pieces of sheet metal whether or not in the form of a can or box.

The can-body (see Figs. 8 and 9) is formed with the usual outwardly-projecting marginal end flange, and the head or end is provided with the usual depressed portion which enters the end of the body and the marginal flange of which projects outwardly beside the flange of the body.

A represents the main frame or standard of the machine, which may be of any suitable or preferred construction and which is provided with the usual horizontal table B and extensions or shelves b at opposite sides thereof for supporting the can bodies and heads in a convenient position for the operator to reach the same to place them in the can-chuck.

The can-chuck comprises a lower horizontal head or mandrel C and an upper horizontal head C', which is arranged above and opposite to the lower chuck-head or mandrel. The upper head is of any suitable construction adapted to bear on the upper headed or un-

headed end of the can. The lower head or mandrel is of a suitable diameter and shape to enter the usual depression of the can-head, so as to form a mandrel to coöperate with the 5 seaming-dies to form and press the double seam. The mandrel is secured to the upper end of a central stud or pin c , which is arranged to move vertically in a bearing c' , secured to or formed on and depending from 10 the table B. The upper chuck-head is secured to the lower end of a vertical stem c'' , which is slidably mounted in bearings c^3 , provided on an upright bracket c^4 , rising from the table. 15 The chuck is operated to grasp and release 15 the can by suitable mechanism. The mechanism shown in the drawings for this purpose is constructed as follows: D represents a horizontal main or drive shaft, which is journaled in suitable bearings in the lower 20 portion of the main frame, and d a drive pulley or wheel thereof, which is driven by a suitable belt or other means. The drive-shaft is provided with a gear-wheel d' , which meshes with and drives a gear-wheel d'' , secured to a 25 counter-shaft E, which is journaled in suitable bearings on the lower portion of the main frame parallel with the drive-shaft. The gear-wheels are so proportioned that the counter-shaft is turned one revolution to each two 30 revolutions of the drive-shaft. F represents a circular cam-disk, which is secured to the counter-shaft and provided with a shallow peripheral depression or notch, and f represents a cam-lever which is fulcrumed on a 35 pivot-pin projecting from a suitable portion of the main frame adjacent to the cam-disk F. One arm of the lever is provided with a roller which bears on the periphery of the cam-disk F, and the other arm of the lever 40 (see Figs. 1 and 3) is connected to the lower end of a vertical rod f' , which is guided in a bearing-opening in the table and in a bearing f'' on the upper portion of the upright bracket c^4 . The upper end of the rod f' is connected 45 to the rear end of a two-part lever f^3 , which is fulcrumed intermediate of its ends on the upright bracket and is connected at its front end to the vertical stem of the upper chuck-head. f^4 , Fig. 1, represents a spring which 50 is coiled about the upright rod f' between a suitable pin or shoulder thereon and the table. This spring acts to depress the vertical rod and hold the roller on the cam-lever on the periphery of the cam-disk F. While the roller 55 bears on the circular portion of the periphery of the cam, the rod is held against the action of its spring and the upper chuck-head is pressed toward the lower chuck-head to grasp and hold the can. When the depression of the 60 cam-disk arrives opposite to the roller on the cam-lever, the latter is permitted to swing, and the spring throws the rod downwardly, raising the upper head of the chuck through the medium of the lever f^3 to release the can. 65 The chuck is opened to release the can at the

completion of each revolution of the counter-shaft E. The upright rod f' is made in two sections, slidably connected by a tube or sleeve f^5 , which is secured to the lower rod-section and loosely surrounds the upper rod-section. 70 The tube is provided with an elongated vertical slot f^6 , in which a pin f^7 on the upper rod-section engages. The pin is held against the upper end of the slot by a spring f^8 , surrounding the upper rod-section, between a pin or shoulder thereon and the upper end of the coupling-sleeve. By this construction the upper chuck-head is yieldingly pressed against the can, thus avoiding the possibility of injuring the latter, and is positively lifted to 80 release the can. Any other suitable mechanism may be employed for operating the chuck to grasp and release the can. 85 G represents the dies for forming and pressing the double seam or joint. The dies are 90 detachably secured in any suitable manner to the inner ends of slide-blocks g , which are arranged to slide radially toward and from the mandrel in suitable ways g' , formed or provided on the table B. In the construction 95 shown the slide-blocks and dies are arranged diagonally with relation to the mandrel, and the inner end of each die is notched or shaped to embrace and operate upon the adjacent corner or meeting portions of the two adjacent sides of the can. When the dies are in 100 their innermost position, their inner ends completely surround the can. It is to be understood that the shape of the dies and their relative arrangement with respect to the can 105 can be changed to suit cans of different diameters and shapes. Each die (see Figs. 6 to 9) is provided with an inclined face g^2 , which supports the flanges $x y$ of the can body and head and is adapted to project beneath the 110 overhanging flange of the mandrel or lower chuck-head, and a curved die face or groove g^3 , which when the die is moved inwardly 115 engages the outer edges of the projecting flanges of the can body and head and rolls the same over to interlock the flanges in a well-known manner, as shown in Fig. 6. This operation of the dies interlocks the flanges of 120 the head and can-body and forms the double seam. After the double seam has been thus 125 formed it is pressed or squeezed to tightly close the same. For this purpose each die is provided above the curved groove g^3 with a vertical pressing-face g^4 . The dies are moved toward the mandrel and can to form the seam or 130 joint by suitable mechanism. That shown in the drawings for this purpose is constructed as follows: H represents a slide-head, which is mounted to move vertically beneath the table of the machine. As shown, the head is guided by vertical rods h , which are secured to and depend from the table, passing through guide-openings in the slide-head. The slide-head is connected to the upper end of a rod or pitman h' , which is provided at its lower end with an 135

eccentric-strap surrounding an eccentric h^2 , secured to the drive-shaft D. The connection between the rod or pitman and the eccentric-strap is preferably made adjustable to properly regulate the throw of the slide-head. h^3 represents links which are arranged radially with respect to the slide-head. These links are pivoted at their inner ends to the slide-head and are pivotally connected at their outer ends to the lower ends of levers h^4 , which are fulcrumed to lugs depending from the table, one lever being arranged beneath each die-block. The upper end of each lever passes through an opening in the table and engages in a recess in the die-block. At each revolution of the drive-shaft the slide-head is raised and lowered by the pitman and eccentric and the die-levers are operated through the medium of the links to move the dies toward and retract them from the mandrel and can. After the dies have been operated, as before stated, to interlock the flanges and have been retracted they are again moved inwardly to cause the vertical faces g^4 to strike the seam and press or tightly close the same. As the vertical pressing-faces of the dies are on a plane above the seam-forming faces, it is necessary to move the dies or the can vertically relative to each other to bring the vertical faces of the dies and the seam on the same plane. Either the can-chuck or the dies could be moved vertically for this purpose. In the construction shown in the drawings the dies are retained in the same horizontal plane and the chuck and can are moved vertically upward after the seam is formed and before it is pressed by mechanism constructed as follows: J, Fig. 4, represents a lever which is arranged beneath the table and is fulcrumed at one end on a pivot j , mounted in suitable lugs depending from the table. The lever is bifurcated or slotted centrally to straddle the vertical stem of the mandrel and the bearing for said stem. The lever is provided with a horizontal pin j' , which extends laterally through vertical slots in the bearing and is connected to the mandrel-stem. The other end of the lever is connected to the upper end of an upright rod j^2 , the lower end of which is provided with a roller j^3 , which travels on the periphery of a cam K, which is secured to the counter-shaft E. The cam is provided with two nearly-semicircular peripheral portions k and k' of different diameters, which are connected by short inclined portions. In the rotation of the cam while the roller bears on the small semicircular portion k the mandrel remains down in position for the first seaming operation. When the forward inclined portion of the cam engages the roller, the rod is raised, and through the lever J the chuck is moved vertically upward far enough to bring the seam opposite to the vertical pressing-faces of the dies. The mandrel is held in its raised position while the larger

semicircular portion of the cam travels past the roller on the upright rod j^2 , and the roller then moves down the rear inclined face and the rod is lowered, returning the mandrel to its lower position. The chuck is held in each position long enough for the dies to be moved inwardly to perform their function and returned to their initial outward position. The chuck and the can are permitted to move upwardly by reason of the construction before described of the vertical operating-rod f' for the upper chuck-head. The upper chuck-head moves up against the tension of the spring f^8 , which while allowing the chuck to move vertically holds the upper head firmly on the can. The drive wheel or pulley d is loosely mounted on the drive-shaft and runs continuously. A clutch-and-trip mechanism controlled by a treadle is provided for coupling the drive-shaft to the drive-wheel to start the operation of the machine after a can body and head have been placed in the chuck and to uncouple the drive-shaft from the drive-wheel and stop the machine after the machine has completed one cycle of operations and formed and pressed the double seam. Any ordinary or preferred means may be employed for this purpose. The clutch-and-trip mechanism shown in the drawings is constructed as follows:

The drive-shaft has secured thereto adjacent to the drive wheel or pulley a clutch-disk L. M represents a friction brake ring or strap, which surrounds and frictionally contacts with the clutch-disk. The brake-ring is stationarily secured to a stud m , projecting from the main frame, and is provided with an adjusting-screw or other device m' for increasing or decreasing the pressure of the brake-ring on the disk. The drive pulley or wheel is provided with a coupling bolt or slide N, which is arranged in a recess therein and is pressed toward the clutch-disk by a spring n in the recess behind the bolt or slide. The clutch-disk is provided with a notch or recess n' , into which the bolt or slide is adapted to be thrown when released by its spring.

O represents a latch, which is mounted on the drive-pulley and pressed by a spring o toward the bolt or slide. The latch is provided with a shoulder or projection adapted to engage in a notch in the bolt or slide and hold the same retracted or away from the clutch-disk against the action of the spring n , so that the drive-wheel rotates freely on the drive-shaft. When the latch is released, the bolt is projected by its spring into the recess in the clutch-disk and the latter and drive-shaft are carried around with the drive pulley or wheel.

P represents a trip-lever for operating the latch and bolt or slide. This lever is fulcrumed on a pivot p , secured to the brake-ring M, which surrounds the clutch-disk. The trip-lever is provided with a short curved

flange p' , which is concentric with the path of the bolt or slide N. This flange is so located and shaped that when the lever is in its raised position (indicated in Fig. 3) the spring-latch on the drive wheel or pulley passes beneath and out of contact with the flange. The lever is normally held raised by a spring p^2 , connected to the lever and to a suitable stationary part, such as an arm p^3 , projecting from the brake-ring. The flange is provided at one end with an inclined face p^4 , which when the lever is depressed engages with a projecting shoulder on the spring-latch and lowers the same, disengaging its shoulder from the shoulder on the bolt or slide, so that the latter is free to be projected by its spring into the recess in the clutch-disk. The clutch-disk and wheel are then coupled together and the clutch-disk and shaft are carried around with the drive-wheel. When the trip-lever is released, it is returned to its upper position by its spring, and an inclined face p^5 on the flange p is carried into the path of a shoulder or projection on the slide or bolt N. When the outer end of the bolt engages said inclined face on the flange, the bolt is retracted from the recess in its clutch-disk. When the bolt is thus retracted, the shoulder on the spring-latch engages the shoulder on the bolt and retains it in its retracted position until it is again released.

The trip-lever is operated to couple the drive-wheel with the clutch-disk by a treadle Q, which is secured at its rear end to a rock-shaft r , journaled in suitable bearings in the lower portion of the frame and projects forwardly into a position to be conveniently reached by the foot of the operator. The rock-shaft r is provided with an arm r' , which is connected to the lower end of a link r^2 , the upper end of which is connected to the trip-lever on the opposite side of its fulcrum from the spring p^2 . When the treadle is depressed, the link is raised and the trip-lever depressed to move its flange downwardly to disengage the latch from the slide or bolt and release the latter.

S represents a projection or lug secured to the hub of the gear-wheel d^2 or to any other suitable part carried by the counter-shaft, and T represents an inclined shoulder or face on the adjacent end of the trip-lever or the link r^2 , connected therewith. The location of the projection S is such that when the coupling bolt or slide is brought around to the flange on the trip-lever for the first time after the treadle has been depressed the trip-lever is depressed by the engagement of the projection S and face T, and the shoulder on the coupling-bolt is not engaged to retract the bolt by the cam-face p^3 on the flange. After the projection S passes the shoulder T the spring p^2 returns the trip-lever to its normal position, and when the coupling-bolt is again brought around to the flange the inclined face

p^5 thereof engages the shoulder on the coupling-bolt and retracts the latter from the recess in the clutch-disk, uncoupling the shaft from the drive-pulley. The shaft is brought to rest very quickly after the bolt is retracted by the brake-ring M. The shaft stops with the recess in the clutch-disk in a position to be again engaged by the bolt or slide when the operator depresses the foot-treadle at the proper point to properly start the operation of the machine.

The operation of the machine is as follows: The operator places the can body and head in the chuck, with the head at the bottom. He then depresses the treadle which operates the clutch mechanism and couples the drive-pulley with the drive-shaft of the machine. The clutch-cam F operates to move the upper clutch-head down to grasp the can, as before explained. The drive-shaft operates the vertical reciprocating head H, which is connected as described to the dies and moves the same inward to form the double seam and then outward again. While the dies are out or separated the chuck, with the can grasped therein, is raised vertically by the described mechanism, and while the chuck and can are held in this raised position the dies are again moved inwardly toward the can to cause their vertical faces to escape and press or tightly close the seam. The dies are then again separated and the chuck lowered to its initial position by the continued rotation of the drive and counter shafts. The automatic trip mechanism then releases the main drive-shaft from the driving-pulley or element, the chuck is opened to release the can, and the machine comes to rest with the parts in the correct position for the operator to remove the can, place another can body and head in the chuck, and again start the machine by depressing the treadle.

If two heads are to be applied to each body, the second head is placed on the body, which is inverted and placed on the mandrel, the seaming operations being repeated.

I claim as my invention—

1. The combination of a support for holding the work stationary in different positions, a seaming-die provided with a portion for forming the seam and a portion for pressing the seam, a stationary guide in which the die is movable toward and from said support, said support in one position holding the seam-flanges opposite to the forming portion of the die, and connected mechanism for changing the position of said support to hold the partially-formed seam opposite to the pressing portion of the die and for moving said die toward said support before and after the change of position of said support, substantially as set forth.

2. In a can-heading machine, the combination of a mandrel for holding the can stationary at different elevations, seaming-dies each

provided with a portion for forming the seam and a portion on a different elevation for pressing the seam, stationary guides in which said dies are movable toward and from said mandrel, said mandrel in one position holding the seam-flanges opposite to the forming portions of the dies, and connected mechanism for changing the elevation of the mandrel to hold the partially-formed seam opposite to the pressing portions of said dies and for moving said dies toward said mandrel before and after the change of elevation of said mandrel, substantially as set forth.

3. In a can-heading machine, the combination of a mandrel for holding the can stationary at different elevations, seaming-dies each having a portion for forming the seam and a portion above said forming portion for pressing the seam, stationary horizontal ways in which said dies slide toward and from said mandrel, said mandrel in one position holding the seam-flanges opposite to the forming portions of the dies, and connected mechanism which moves said dies to and from the seam, then elevates the mandrel to position the partially-formed seam opposite to the pressing portions of the dies, and then moves the dies to press the seam, substantially as set forth.

4. In a can-heading machine, the combination of a mandrel for supporting the can, seaming-dies, horizontal ways in which said dies are mounted to slide toward said mandrel, each die having a curved face for forming the seam and a substantially straight face above said curved face for pressing the seam, means for raising said mandrel to position the seam in operative relation to the pressing portions of said dies, and means for moving said dies toward said mandrel before and after the latter is raised, substantially as set forth.

5. In a can-heading machine, the combination of a stationary frame provided with a horizontal table, a vertically-movable mandrel for holding the can stationary at different elevations, stationary radial ways on said table, seaming-dies movable in said ways toward and from the mandrel and each provided with a portion for forming the seam, and a portion above said forming portion for pressing the seam, said mandrel in one position holding the seam-flanges opposite to the form-

ing portions of the dies, and connected mechanism on said frame which moves the dies to form the seam, then elevates the mandrel to position the partially-formed seam opposite to the pressing portions of the dies, and then moves the dies to press the seam, substantially as set forth.

6. In a can-heading machine, the combination of a frame provided with a horizontal table, a mandrel for supporting the can mounted to move vertically in a bearing on said table, dies movable toward and from said mandrel in radial ways on said table, each die being provided with a portion for forming the seam and a portion above the forming portion for pressing the seam, a rotary shaft, connections between said shaft and said dies for moving the same toward and from said mandrel, a rotary shaft geared to said first-mentioned shaft to make one revolution to each two revolutions of said first-mentioned shaft, a cam carried by said second shaft, and a lever connected to said mandrel and operated by said cam to raise said mandrel after one revolution of said first-mentioned shaft, substantially as set forth.

7. In a can-heading machine, the combination of a chuck comprising oppositely-arranged heads for holding the can, means including an operating-rod for moving one of said heads toward the other to grasp the can, seaming-dies each provided with a portion for forming the seam and a portion for pressing the seam, said chuck in one position holding the seam-flanges opposite to the forming portions of the dies, means for moving one of said chuck-heads to hold the partially-formed can-seam opposite to the pressing portions of said seaming-dies, and means for moving said dies toward said chuck before and after the change of position of the latter, said operating-rod having a yielding portion whereby the chuck-head operated thereby is adapted to move with the other chuck-head without releasing the can, substantially as set forth.

Witness my hand this 30th day of September, 1902.
